CENTRIFUGAL CLUTCH CONTROL

Arnold Pitt, Toronto, Ontario, Canada, assignor
to Massey-Harris Co., Ltd., Toronto, Ontario,
Canada, a corporation of Canada

Application August 25, 1945, Serial No. 612,623

2 Claims. (Cl. 192—103)

1

The present invention relates to a starting clutch for devices such as cream separators, wherein the operating parts rotate at very high speed, the operating parts having considerable weight, thus possessing high initial inertia, so as to require great initial power for starting.

When a cream separator is electric motor driven, the motor must be much larger than is necessary to normally operate the separator in order to avoid possible injury to the motor or connecting parts. Otherwise the motor must operate at a considerable overload for the starting period and this endangers the motor, the brushes, motor connections and switches. In either event there is necessarily a very high peak load during the starting period.

The present invention provides means whereby the driving power required for first starting is practically zero and then power is added to the motor gradually until the operating parts turn at full speed thus to avoid a dangerous peak load and the necessity for an unusually large motor. The device is adapted to form a non slipping connection between the driving and driven members before full speed is reached.

In my device the driven member and separator rotor are first operated by a predetermined friction, the weight of the centrifugally operated clutch blocks on the driven element being such as will gradually increase the friction due to rotation of the driven element, the effect being to finally complete the engagement between the driving and driven elements a short time before the driven element reaches full speed. The arrangement and design of the centrifugal thrust is such as will increase the frictional contact to the driver in proportion to the square of the rotational speed of the driven member.

In my device the driver reaches a considerable speed before there is an appreciable load on the motor, therefore it protects the motor and gears from excessive starting strains, which might even be caused by a strong man who is in a hurry to get the device started. In other words a minimum size motor and minimum size transmission may be used with safety when my centrifugal clutch control is used.

To these and other useful ends my device consists of parts, combinations of parts or their equivalents and mode of operation as hereinafter described and claimed and shown in the accompanying drawings in which:

Fig. 1 is a longitudinal sectional view of my device and Fig. 2 is a transverse sectional view taken on line 2—2 of Figure 1.

2

As thus illustrated the driven shaft of my centrifugal clutch is designated by reference character 10 having secured thereto a collar 11. A collar 12 preferably rotatably rests on member 14 and shaft 10 has an enlargement 13 which rests on collar 12. This enlargement for part of its length is cut away as at 14—14 as shown in the figures. A hub 15 is at its lower end preferably rotatably mounted on a collar 12 and resting on a shoulder 16 as clearly illustrated in Figure 1. Hub 15 has integrally formed thereon a circular drum 15' which is provided with a cap 17 through which shaft 10 rotatably protrudes.

Mount on surfaces 14 clutch blocks 18—18, each being a segment of a circle these clutch blocks being adapted to fit against the inner machined surface 19 of member 15 and lie close to surfaces 14. Member 15' is preferably provided with a V belt groove 20, so this member may be driven by a belt from a motor or otherwise.

Generally shaft 10 is operatively connected to the separator rotor unit by means of a series of worm gears, this being necessary because the separator units may operate normally at an 8000 revolution per minute speed; therefore a considerable increase in speed is necessary between shaft 10 and the separator rotor.

An opening 25 is provided through the flattened portion of member 13 and apertures 26 are provided in members 18 which register with opening 25. I provide a light spring 27 which is positioned as shown in the figures and adapted to exert a very light pressure against members 18, so members 18 will lightly contact surface 19 when member 10 is at rest.

Thus it will be seen that when the motor or other power means which is operatively connected to member 15 is started, the only load to be carried by the motor is represented by the light friction between members 18 and 19 and between members 11 and 12 and members 12 and 15. This friction however is enough to start rotation of the driven element.

It will be seen that the motor starts with practically no load and that it operates under a comparatively light load until shaft 10 is turned at considerable speed and then as the speed of shaft 10 is increased the load will be increased at first slowly and then more and more rapidly, until member 10 has at least reached more than one half normal speed. Clearly the action of the flat surfaces 14 will tend to urge members 18 outward as the power required is increased, thus to cooperate with centrifugal force to substantially

3

lock members 15 and 18 together when maximum power and speed has been reached.

From the foregoing it will be seen that with applicant's device a motor design to carry the normal load is sufficient as a driver and that all operating connections between the driver and separator rotor will not be subjected to high peak loads when starting. In other words the motor and all its connecting parts including the separator transmission may be designed for the normal operating load of the separator or other device irrespective of inertia of the separator, rotor or other element driven by the clutch.

It will be understood that the separating element, the transmission element and the transmission from shaft 10 to the separating element are mounted on ball bearings so that there is very little friction necessary between members 15 and 18 to start the separator element to turning, these mountings being so near frictionless that applicant's device will generally operate successfully without the use of spring 27 because of the friction between members 11, and 12 and 12 and 15.

Applicant's device is novel because the centrifugal clutch member is mounted on the driven shaft, the driving motor being connected to housing 15 which is at starting practically free to turn and that the clutch acts very gently at starting and increases its grip on the driving member as the speed is increased, that this increase clutching effect acts on the basis of the square of the increase in speed of the driven member.

Having thus shown and described my invention, I claim:

1. A self-serving automatic clutch of the character described comprising in combination, a driven shaft, a driving hub rotatably mounted on said driven shaft and means for driving the same, said driving hub having extended from one end thereof a circular drum, said driven shaft having secured thereon a circular

4

projection, another projection integral with the first projection having flat surfaces on opposite sides thereof with a length substantially equivalent to the diameter of the first projection and a thickness substantially equal to the diameter of the driven shaft, the length of said other projection being substantially one half the inside diameter of said drum, a pair of clutch blocks formed in the shape of segments, their flat sides adapted to be in juxtaposition with the flat sides of said other projection and their curved surfaces adapted to permanently rest uniformly on the inside of said drum, apertures in said clutch blocks and a hole through said flattened extension and shaft registering with said clutch block apertures, a light push spring extending through the hole in said other projection and shaft and into said clutch block apertures.

2. A device as recited in claim 1 including, said
20 drum having a cap secured to its outer end
through which said driving shaft rotatably ex-
tends forming a closure for the drum.

ARNOLD PITT.
